APPARATUS FOR FORMING A MULTIPLE WEB PRODUCT

Harlan W. Hirschy, Neenah, Wis., assignor to Kimberly-Clark Corporation, Neenah, Wis., a corporation of Delaware

Application December 17, 1954, Serial No. 476,027

6 Claims. (Cl. 154—1.7)

The present invention is concerned with a method and an apparatus for forming thread and web structures in a continuous manner, and is primarily directed to the manufacture of thread and web products in which means are provided for improving the physical properties of the product by controlled orientation of the elements making up the product.

While the present invention has applicability to the manufacture of numerous types of products of widely different characteristics, the invention will be described as it is applied to the field of nonwoven web and thread textile products.

In some fields, nonwoven webs composed of cotton fibers, rayon fibers, or mixtures of various natural or synthetic fibers have very distinct advantages over woven textile webs. The light weight, softness, and the low cost of such webs are some of the characteristics which make them useful as replacements for the considerably heavier and less flexible cotton gauze materials. The major drawback to the use of nonwoven webs has, of course, been their inherent lack of strength, when compared with a woven material of the same weight per unit area.

The strength of a nonwoven web in a given direction is directly related to the relative number of fibers of the web extending in that direction. With conventional apparatus for forming nonwoven webs, the majority of the fibers extend generally in the machine direction of the web so that the maximum strength occurs lengthwise of the web and much less strength is obtained in the cross-machine or transverse direction in the web.

For many applications of nonwoven web structures, it is important that the transverse strength of the web be comparable to, or even greater than, the strength in the machine direction. One practical means for accomplishing this result is to provide a laminated structure in which the fibers of one of the webs are disposed primarily along the longitudinal direction of the web, and the fibers in an overlying web are arranged substantially perpendicular to the fibers in the first web.

Such products are very difficult to manufacture, especially as a continuous operation, although it should be mentioned that some paperboard cores are made of two plies of paper with the machine directions of the separate plies at an angle to each other. However, because of the method and apparatus employed in combining the paper plies in this product, the finished core results in a dual helix of paper webs in which the maximum strength is neither along the longitudinal nor the transverse axis of the product.

Some other types of equipment have been suggested for making more nearly perfect crosslaid webs. However, such equipment is usually discontinuous in operation and in any event, operates at an extremely slow speed. The provision of an apparatus for manufacturing such webs in a continuous and rapid manner is one of the primary objects of the present invention.

2

The present invention is also concerned with the provision of methods and apparatus for making gauze-like web or sheet products from sets of strands which are laid in a cross pattern one on the other. Other objects of the invention include the provision of a method for manufacturing a strengthened nonwoven web in a continuous, rapid process, and the provision of novel apparatus for continuously laying a cross sheet or a pattern of threads onto a moving supporting surface which may also include a sheet or a pattern of threads, and for cutting the cross sheet to provide a continuous cross-laid product.

The invention also includes the provision of certain structural and operational features of great importance in accomplishing the above stated general objects of the invention.

The present application is a continuation-in-part of my prior application, Serial No. 390,029, filed November 3, 1953, now abandoned, and is assigned to the assignee of that application.

Basically, the method involved in the present invention consists in training a supporting surface into a continuously moving helix, wrapping around the helix a second helix consisting of a sheet or of spaced strands such that the predominating direction of the fiber lay of the sheet, or the direction of the reinforcing strands, is at a substantial and predetermined angle to the direction of movement of the supporting surface, to the end that the resulting direction of lay will be at an angle, also predetermined, and preferably a right angle to the machine direction of the finished product, and then continuously cutting the second helix laterally in a direction parallel to an edge of the supporting surface.

Several forms of apparatus for carrying out the above-described method are illustrated in the drawings, in which:

Figure 1 is a view in perspective of an apparatus for laying a sheet material on another sheet;

Figure 2 is a plan view of the apparatus shown in Figure 1;

Figure 3 is a fragmentary, somewhat enlarged view of the drum and mandrel assembly of the apparatus illustrated in the preceding figures;

Figure 4 is a somewhat schematic view of the mandrel and the two sheets trained around the mandrel, illustrating the manner in which the cross sheet or other medium is continuously cut after its application to the main sheet or other medium;

Figure 5 is an enlarged, fragmentary view of a cutting mechanism which may be employed;

Figure 6 is an end view of the mandrel in the direction of the mandrel axis;

Figure 7 is an enlarged, fragmentary view of a typical completed nonwoven web, the view being partially broken away to illustrate the structure of the component plies;

Figure 8 is a somewhat schematic drawing of a machine for applying a pattern of threads onto a web;

Figure 9 is a fragmentary view of a gauze-like product which may be produced with the machine shown in Figure 8;

Figure 10 is a fragmentary view of an overlapped web structure also falling within the scope of the present invention;

Figure 11 is a schematic view illustrating the various angular relationships which occur during the cross laying of the web, thread, or other mediums, one upon the other;

Figure 12 is a fragmentary view, partially in section, of an improved mandrel construction having especial utility in connection with apparatus of the general type shown in Figures 1 and 8;

Figure 13 is an enlarged sectional view taken on the line 13—13 of Figure 12; and

Figure 14 is a perspective view of a particular belt construction especially useful in the practice of the invention.

In Figures 1 and 2, reference numeral 10 indicates generally a frame assembly which supports the various elements in the cross laying assembly. The upper beam sections of the frame 10, indicated at 11, have a pair of angularly disposed shaft supports 12 which tightly engage a shaft 13 extending from a stationary mandrel 14 and hold it against rotation. The mandrel 14 is provided along a portion of its outer surface with a helical, raised rib 16 to serve as a guide means for an endless flexible belt 17 composed of canvas or other flexible material. The belt 17 is guided onto the surface of the mandrel 14 from a roller 18 and extends between the lands provided by the rib 16; the width of the belt 17, measured on a line parallel to the axis of the mandrel 14, is slightly less than the pitch of the helix provided by the rib 16.

For most types of webs, it will be desirable to use a belt of this nature in guiding the web around the mandrel, but the presence of the belt may not be required for webs which can conform to the mandrel surface without breaking upon the application of sufficient force to pull the web about the mandrel.

The belt 17 makes at least one complete turn about the stationary mandrel 14 and then is trained over a driven roller 19. The latter has a shaft 21 supported by a block 22 slidably received within a slot of a bracket 23 carried by the frame 10. Movement of the block 22 within the slot thus provides a means for adjusting the tension of the belt 17. The belt then passes over a roller 24 having a shaft 26 supported within a block 27 also slidably received in the slot in the bracket 23. The relative position of the roller 24 with respect to the roller 19 can be adjusted by movement of a rod 28 attached to the block 27.

The belt 17 after being trained around the roller 24 passes over a guide roller 29 located centrally of the frame 10, and is then trained around a roller 31 located near the base of the frame 10. The belt is then passed lengthwise of the machine and may be given a half twist so that it can be trained around a vertically disposed tension roller 32 (Figure 2).

The belt 17 is then trained around a second vertical tension roller 33 after which it is given another half twist. The belt is then received about a guide roller 35 and finally passes over the roller 18, completing its loop.

As the belt 17 is moved along the mandrel 14 in the illustrated structure, it carries with it a longitudinal web or sheet medium 36. This may comprise a sheet of paper or nonwoven fibers, as illustrated, or it may comprise threads, or other material. The medium 36 is conveniently deposited on the belt 17 from a suitable supply means, such as the roll of sheet material illustrated at 37 in Figures 1 and 2, and the apparatus desirably includes a suitably disposed roll 38 for guiding and slightly tensioning the sheet 36 or other medium as it is deposited on the upper surface of the belt 17. The axis of the illustrated supply roll 37 is parallel to the axis of the belt guide roll 18, and the supply roll 37 is conveniently disposed a short distance above and to the rear of the belt guide roll 18.

In the illustrated embodiment of the invention, the width of the sheet 36 is comparable to the width of the belt 17 and when the sheet 36 is of nonwoven material, the fibers in the sheet 36 will lie predominantly in the machine direction, i. e., lengthwise of the sheet, so that the maximum strength of this sheet is along its long dimension. Rollers can be provided for pressing the sheet 36 onto the belt 17, or adhesive spots may be employed on the sheet for holding it on the belt, but ordinarily these are unnecessary, as a thin, nonwoven

web will readily be guided by the surface of a canvas belt.

The mandrel 14 is disposed with its axis substantially coincident with the axis of a hollow rotating carrier 39, comprising a pair of end flanges 41 and 42 separated by means of spacers 43. The rim of the carrier 39 is mounted for rotation on a set of four wheels 44 (Figure 1) which are supported for rotation on a bracket 46 secured to an intermediate portion of the frame 10.

The carrier 39 has a pair of angularly disposed support brackets 47 and 48 (Figure 2) which journal a shaft 49 for rotation therein. The shaft 49 carries the second medium which is applied, in crosswise relationship, to the first medium during the operation of the apparatus. In the illustrated apparatus, the second medium comprises a sheet 52 of nonwoven fibers which is unwound from a suitable supply roll 51 disposed on the shaft 49. The fibers in the sheet 52 extend predominately along the length of the sheet so that the maximum strength of the sheet is in that direction.

The sheet 52 passes over a guide roller 53 and is then wrapped around the main sheet 36 carried by the belt 17 (Figures 3 and 4). If desired, small spots of adhesive can be provided on the sheet 52 to hold it onto the sheet 36 until the combined sheets leave the machine. The angular positions of the roll 51 and the roller 53 are quite critical, and the support mechanism for the members 51 and 53 should be adjustable. When laying one web upon another, or when laying a series of cross webs to produce products of the type shown in Figure 10, freedom from distortion will be achieved only if the sheet 52 is trained about the mandrel so that the sheet 52 intersects the sheet 36 (or the belt 17) along a continuous straight line of intersection extending the full width of the sheet 52. Thus, the sheet 36 in being pulled across the mandrel 14 forms a helix which moves about the mandrel 14 in a counter-clockwise direction as viewed from the end of the carrier 39 at which the sheet 36 enters. At the same time, the relative movement between the roll 51 and the mandrel 14 resulting from the rotation of the carrier 39 about the mandrel 14, which rotation is also counter-clockwise, as viewed from the end of the carrier at which the sheet enters, wraps the sheet 52 in another helix which intersects the helix of the sheet 36 at right angles thereto.

When using the particular apparatus shown in the drawings, the same angular relationships will be observed where the sheet 52 is replaced by a plurality of threads or other strands, i. e., the points of tangency of the strands as they are trained about the helically moving sheet 36 will define a straight line parallel to the axis of the mandrel. However, the laying of threads upon webs or other threads permits a considerably wider variation in the parameters of the process, and these will be discussed in a subsequent portion of this specification.

After the crosswise reinforcing medium, whether of threads or of sheet material, has been applied to the medium trained about the mandrel, the sheet 36 in the structure of Figures 1 and 2, the crosswise medium, the sheet 52 in the illustrated structure, is continuously slit by means of a slitting device 54, best illustrated in Figure 5 of the drawings. As seen in that drawing, the slitting device 54 may comprise a small motor 56 which drives a shaft 57 upon which a disc cutter 58 is secured. The edge of the disc cutter 58 is positioned so that it cuts the laminated sheets at one edge of the main sheet 36, parallel to the marginal edge of the main sheet 36. The edge of the disc cutter 58 extends into the small space provided between the belt 17 and the rib 16, as shown. The cutting means 54 is secured to a stationary part of the frame 10 by means of a support arm 59 (Figure 3).

A common drive system is employed to pull the belt 17 across the mandrel 14 and to rotate the carrier 39. This drive system may include a variable speed motor 61 which drives a variable speed transmission 62 through

a chain and sprocket assembly 63 (Figure 2). The output shaft of the transmission 62 operates a speed reducer (not shown) which in turn is coupled to a sprocket 64 (Figure 1) by means of a chain 66 to drive the roller 19.

The energization of the motor 61 is controlled by means of a motor control unit 67, electrically connected thereto. A hand operated control 68 (Figure 2) provides a means for adjusting the input to the motor. The shaft of the motor 61 also is coupled to a speed reducer 69 by means of a chain and sprocket assembly 70 (not shown in detail), and the output of the speed reducer 69 is coupled by means of a sprocket and chain assembly 71 to a shaft 72 to which a beveled gear 73 is secured. The beveled gear 73 engages an annular gear 74 concentric with the end flange 41 of the drum 39 to rotate the carrier 39 about an axis substantially coinciding with the axis of the mandrel 14.

The means for pulling the belt across the mandrel 14, as well as the means for driving the carrier 39 illustrated in the drawings, represent only one possible drive system which may be employed, and it will be recognized that various means could be provided to accomplish the same results.

A finished web, as it is delivered by the machine in the vicinity of the roll 19, is illustrated in Figure 7 of the drawings. As seen in this figure, the underlying sheet 36 has a significant proportion of its fibers aligned in the longitudinal direction of the web, and the cross sheet 52, of slightly greater width than the sheet 36, has its fibers predominantly in the direction perpendicular to the direction of the longitudinal fibers in the sheet 36. The laminated web structure can be printed in spaced areas with suitable adhesives such as vinyl polymers, polyethylene, and the like in order to further increase the strength of the laminate according to any of a variety of processes.

A modified form of the invention is illustrated in Figure 8 of the drawings. In this embodiment of the invention, which is especially adapted to the manufacture of cross laid thread products, such as are illustrated in Figure 9, or to products which combine sheets and reinforcing threads, means are provided to apply a pattern of threads in a network over a moving web or other medium. As seen in Figure 8, a sheet 81 which may be a sheet of nonwoven fabric or other sheet material, is received under a roll 82 whereupon it is guided onto the surface of a moving belt 83 by means of a roller 84. As the sheet 81 and the belt 83 move to the right as seen in Figure 8, the sheet 81 is overlaid with a pattern of longitudinal threads 86 which are being constantly supplied from a creel 87. The thread cones included in the creel 87 supply a plurality of series of threads 86 which pass through a plurality of guide means 88 arranged to direct the threads over a first guide bar 89 and about a second horizontally disposed guide bar 91. The threads 86 then pass over a comb array 92, following which the threads are given a coat of adhesive from an applicator roll 93 in contact with the threads. A suitable adhesive such as a thermoplastic resinous composition is applied to the surface of the applicator roll 93 from a roll 94 in contact therewith.

After the threads 86 have received a coating of adhesive, the thread reinforced web and the belt 83 carrying the web are guided about a stationary, cylindrical mandrel 96 so as to form thereon a first helix, as shown. The belt 83, of course, is continuously pulled about the stationary mandrel 96 by means not shown in the drawings.

The mandrel 96 is substantially coaxial with a rotating carrier or disc 97 which applies threads to the moving web in a direction normal to the direction of the previously applied threads. In other words, the carrier 97 is arranged to wrap additional threads in the form of helices at right angles to the helices formed by the previously deposited threads as those threads pass about the mandrel. The points of contact in the illustrated em-

bodiment form equally spaced points on a right circular section of the mandrel, instead of the straight line of intersection described in connection with the previously described embodiment. As previously pointed out, the line of intersection in the case of thread laying may vary considerably depending upon the manner in which the threads are received on the supporting surface.

The carrier 97 supports a plurality of circumferentially spaced cones of thread supported on both sides thereof. The cones 98 feed threads 99 centrally of the carrier disc 97 and over an annular series of guide means 101 onto the surface of the moving belt or sheet.

As the belt 83 is removed from the mandrel, a slitter 102 engages the web to sever the cross strands parallel to the marginal edge of the moving sheet.

The resulting thread reinforced product is then separated from the belt 83, the belt 83 passing over a series of rollers, including rollers 103 and 104, before returning to the inlet end of the machine. The thread reinforced product may be then passed about a heated roller 106 in contact with a heat resistant roller 107 in order to cause the adhesive applied to the strands to become more plastic and to flow about the junctions of the longitudinal and transverse threads. With certain type of adhesives, a better bond is thereby secured between the web and the pattern of threads, but the use of a heated roll or rolls is optional.

After leaving the surface of the roll 107, the completed product will normally be conveyed, as by the roll 108, to a slitting means 109 where the web will be cut into any desired width. After leaving the slitting means 109, the web strips are wound about a take-up reel 111 by means of a pair of winding rolls 112 and 113.

It will be appreciated that various other mechanical means such as gears, belts, chains, discs or the like may be employed to carry the cross laid material on a path which is coaxial with the axis of the mandrel.

More than one layer of sheet material may be embodied into the finished product. For example, an additional sheet or web, or a series of sheets or webs, may be applied to the upper surface of the threads 86, and the underlying sheet or sheets, at any convenient point prior to the application of the threads 99. Similarly, additional sheets, or even additional sets of longitudinally extending threads may be applied to the product after the application of the cross threads 99.

Also, the web or sheet components may be omitted entirely, this resulting in the production of a product of the type illustrated in Figure 9. As shown in that figure, the thread-only product, which has particular utility in instances where woven products such as gauze have heretofore been used, consists merely in the two sets of strands adhesively attached to each other at at least some of their junctions.

For some applications, it is important that the strength of a product in its short dimension be as great as, or greater than, its strength in its long dimension. A typical example of a product of this type is a boxmaker's tape which is used to join the edges of a corner of a cardboard box. This type of product can be made on a machine of the type illustrated in Figures 1 and 2 by eliminating the main sheet 36 and providing two or more rolls of paper or other material in circumferentially spaced relation within the carrier 39. The resulting product is illustrated in Figure 10, which illustrates a pair of overlapped paper strips 116 and 117, both of which have their maximum strength in the machine direction of the paper, i. e. is perpendicular to the long dimension of the finished product. The strips should be adhesively or otherwise joined to each other in the region of their overlapping edges.

The geometric relationships involved in designing an apparatus according to the present invention are critical, and will now be described in some detail.

Turning now to the schematic showing in Figure 11, the distances shown are identified as follows:

AB is the effective width of the belt on a line parallel to the axis of the mandrel, this distance being equal to the pitch of the helical rib 16;

BD is equal to the circumference of a right circular section of the mandrel (simply the circumference of the mandrel if no belt is employed, or the outer circumference of the belt as it is trained about the mandrel);

BG is the effective width of the belt measured along a line perpendicular to its length (or the width of the sheet if no belt is used);

AD is the length of the helix, comprising one complete turn from a point B around the mandrel to point A;

CF is the transverse width of the cross sheet;

CD is the repeating length of the cross lay pattern, measured along the length of the main sheet for the condition where the carrier makes one revolution for each advance of the sheet through the distance CD;

AE is the opening available for cross laying, i. e., the available space on the main web on which the second web can be laid, and

α is the angular deviation between the direction of longitudinal movement of the second web and a perpendicular to the direction of longitudinal movement of the first web, i. e., the angle between the edge of the second web or other medium and a perpendicular to the edge or direction of movement of the first web, when the second web is in position on the first web; and

θ is the angle between the mandrel axis and the direction of longitudinal movement of the first web or other medium. This angle is also the angle of inclination of the edge of the supporting belt (or the first medium, if that medium be of sheet material) to the line along which the belt (or the first medium, if that medium be of sheet material) intersects the mandrel.

Normally, the width of the main sheet and cross sheet, and the angle of the lay will be predetermined, and the factors to be determined will be the inclination of the main web to the mandrel, the diameter of the mandrel, and the ratio of belt speed to the speed at which the cross laid material is applied to the mandrel. There are practical limitations in the design which must be taken into consideration. For example, if the angle of inclination of the supporting surface to the line of its intersection with the mandrel, angle θ in Figure 11, is too large, the pull on the belt will be taken up along the mandrel and not by the belt. If the angle is too small, the belt will slip off the mandrel. For practical perpendicular cross laying, this angle will be in the range of from 30° to 60°.

For satisfactory operation at high speed, it will be found important to provide special support means for the belt, or first medium, as that element is moved on the surface of the mandrel. In the particular apparatus illustrated in the drawings, that support is provided by an air cushion formed intermediate the inner surface of the belt or first medium and the outer surface of the mandrel. This will be described in further detail in connection with Figures 12, 13 and 14.

In the following analysis, it is assumed that the carrier for the cross laid medium makes one revolution for each repeating length of the cross lay pattern, represented by the length CD in Figure 11. Those skilled in the art will appreciate that other speed relationships are possible in the practice of the present invention.

From an inspection of the angular relationships and the application of the law of sines, it will be seen that:

$$\cos \theta = \frac{BG}{BD} \quad (1) \quad 70$$

$$CF = CD \cos \alpha \quad (2)$$

$$BG = BC \cos \alpha \quad (3) \quad 75$$

Applying the law of sines:

$$\frac{CD}{\sin(\theta-\alpha)} = \frac{BC}{\cos \theta}$$

$$CD = BC \cdot \frac{\sin(\theta-\alpha)}{\cos \theta} \quad (4)$$

Multiplying both sides by $\cos \alpha$ and using Equations 2 and 3:

$$CF = BG \cdot \frac{\sin(\theta-\alpha)}{\cos \theta} \quad (5)$$

Equation 5 can be solved for θ as follows:

$$CF = BG \cdot \frac{\sin \theta \cos \alpha - \cos \theta \sin \alpha}{\cos \theta}$$

$$CF = BG \cdot (\tan \theta \cos \alpha - \sin \alpha)$$

$$CF + (BG \sin \alpha) = (BG \cos \alpha) \tan \theta$$

and

$$\tan \theta = \frac{CF + BG \sin \alpha}{BG \cos \alpha} \quad (6)$$

so that the angle θ may be calculated from the two web widths and the angle between the webs.

It will further be seen that:

$$AE = AC \cos \alpha \quad (7)$$

Applying the law of sines:

$$\frac{AC}{\sin(90^\circ - \theta + \alpha)} = \frac{BC}{\sin \theta}$$

$$AC = BC \cdot \frac{\cos(\theta-\alpha)}{\sin \theta} \quad (8)$$

Multiplying both sides by $\cos \alpha$, and substituting Equations 3 and 7:

$$AE = BG \cdot \frac{\cos(\theta-\alpha)}{\sin \theta} \quad (9)$$

Equation 9 gives the opening available for cross laying. If the distance AE is less than the distance CF, then the cross web must be split up into increments, and applied in sequence, or the opening increased by wrapping the belt another turn about the mandrel.

In the case of laying individual threads, instead of a cross web, it will be seen that if N threads equally spaced by a distance S are employed, Equation 6 will become:

$$\tan \theta = \frac{N \cdot S + BG \sin \alpha}{BG \cos \alpha} \quad (10)$$

The following specific examples illustrate the application of these equations to specific cases.

Example 1

It is desired to produce a product consisting of a web 40 inches wide reinforced with strands spaced approximately 0.2 inch apart at right angles to the length of the web. The belt thickness is 0.25 inch and the rib on the mandrel is to be 0.5 inch in width (measured at a right angle to the rib helix).

As an approximation, assume a value of 45° for the angle θ , and solve for the value N , the number of strands by means of Equation 10:

$$N = \frac{\tan \theta (BG \cos \alpha) - BG \sin \alpha}{S}$$

$$= \frac{\tan 45^\circ [(40 + 0.5) \cos 0^\circ] - (40 + 0.5) \sin 0^\circ}{0.2}$$

$$N = 202.5 \text{ strands}$$

For convenience, N will be taken as 200.

The angle θ is then calculated for the value of N from Equation 10 as follows:

$$\tan \theta = \frac{200(0.2)}{40.5} = 0.98765$$

$$\theta = 44^\circ 38.64'$$

The effective diameter, D , of the mandrel (actual diameter plus twice the thickness of the belt) may then be calculated from Equation 1:

$$D = \frac{BG}{\pi \cos \theta}$$

$$D = 18.119 \text{ in.}$$

$$\text{Diameter of mandrel} = 18.119 \text{ in.} - 0.5 = 17.619 \text{ in.}$$

Example II

For producing the same product as specified in Example I, but where the angle θ between the main sheet and the mandrel is to be about 60° , the following values are obtained:

$$N = \frac{(40.5)(\tan 60^\circ)}{0.2} = 350.75$$

Choosing the convenient value of $N=350$,

$$\tan \theta = \frac{350(0.2)}{40.5} = 1.7284$$

$$\theta = 59^\circ 56.83'$$

Calculating for the mandrel diameter:

$$D = \frac{40.5}{\pi \cos 60^\circ} = 25.742$$

$$\text{Diameter} = 25.742 - 0.5 = 25.242 \text{ in.}$$

Example III

The product desired in this case consists of a main sheet 40 inches wide and a cross sheet 40 inches wide at right angles to the main sheet. The width of the rib is to be 0.5 inch as previously.

Using Equation 6:

$$\tan \theta = \frac{40}{40.5} = 0.98765$$

$$\theta = 44^\circ 38.64'$$

Solving for the mandrel diameter from Equation 1:

$$D = \frac{40.5}{\pi \cos \theta} = 18.119 \text{ in.}$$

$$\text{Diameter of mandrel} = 18.119 - 0.5 = 17.619 \text{ in.}$$

The available opening in this case from Equation 9 would be:

$$AE = \frac{40.5 \cos \theta}{\sin \theta} = 41.006 \text{ in.}$$

Since this value exceeds the width of the cross web, the desired product can be obtained by using a single roll of the cross web.

Example IV

In this case, a cross web measuring 70 inches in width was to be laid at right angles to a main web 40 inches in width, using the same rib width and belt thickness as previously.

Solving for the angle:

$$\tan \theta = \frac{70}{40.5} = 1.7284$$

$$\theta = 59^\circ 56.83'$$

The mandrel diameter is then calculated as follows:

$$D = \frac{40.5}{\pi \cos \theta} = 25.742 \text{ in.}$$

$$\text{Diameter} = 25.742 - 0.5 = 25.242 \text{ in.}$$

The available opening, AE , is then calculated as follows:

$$AE = \frac{40.5 \cos \theta}{\sin \theta} = 23.435 \text{ in.}$$

Since the available opening is slightly more than one-third the width of the cross web, the cross web would have to be laid in at least three parts, as by slitting the 70 inches web into three equal strips and laying them in side-by-side relationship along the main web as it moves about the mandrel.

Example V

It was desired to use a sheet 40 inches wide, a rib 0.5 inch wide, a belt 0.025 inch thick, a spacing of 0.2 inch between threads, and a cross lay angle of 60° . The desired angle of intersection (angle θ) was about 45° .

The distance CF in Figure 11 in the case of strands is represented by the repeating width of the cross lay. Hence from Equation 5:

$$0.2N = (40 + 0.5) \frac{\sin (45^\circ - 30^\circ)}{\cos 45^\circ}$$

$$N = 74.12$$

Choosing the convenient value of $N=75$, the repeating width of the cross lay is then $75 \times 0.2 = 15$ in.

Equation 10 can be solved for $\tan \theta$ exactly as follows:

$$\tan \theta = \frac{15 + (40.5) \sin 30^\circ}{40.5 \cos 30^\circ} = 1.0050$$

and

$$\theta = 45^\circ 0.83'$$

The diameter, D , is then obtained from Equation 1:

$$D = \frac{40.5}{\pi \cos \theta} = 18.236 \text{ in.}$$

The actual diameter of the mandrel is then

$$18.236 - 0.500 = 17.736 \text{ in.}$$

As previously indicated, the above examples are predicated upon the use of a specific speed ratio between the supporting surface and the cross laid medium. In the case of thread laying, the speed relationships are usually the easiest to vary in order to change the angle of inclination between the two surfaces. The following example illustrates the effect of speed variation.

Example VI

With the same equipment as employed in Example I, the carrier made one revolution for every 40 inches advance of the web material. Assume now that the carrier is to make n revolutions for each 40 inch advance of the web. With this condition, it will be seen that the repeating length of the pattern will become:

$$40/n \text{ inches}$$

Referring again to Figure 11, it will be observed that in this situation:

$$CD = \frac{GD}{n} \quad (11)$$

and:

$$\tan \alpha = \frac{CG - GD - CD}{BG} = \frac{GD - \left(\frac{GD}{n}\right)}{BG}$$

so:

$$\tan \alpha = \frac{n-1}{n} \cdot \frac{GD}{BG} = \frac{n-1}{n} \cdot \tan \theta \quad (12)$$

If the 200 strands employed in Example I are released from points equally spaced along the carrier, the new cross lay at the new angle will still register accurately, but the spacing of the strands (measured parallel to the long dimension of the web) will change. From Figure 11, it will be seen that the 200 strands will now occupy the space CD instead of the space GD, and they will be parallel to the line CB. The spacing of the strands will therefore be:

$$\text{New spacing} = \frac{CD}{N} = \frac{\left(\frac{GD}{n}\right)}{N} \cdot \cos \alpha = \frac{GD}{N} \cdot \cos \alpha \quad (13)$$

Since

$$\frac{GD}{N}$$

was the spacing in the original example, the formula for the new spacing may be written:

$$\text{New spacing} = (\text{original spacing}) \cdot \frac{\cos \alpha}{n} \quad (13)$$

To illustrate the above with specific examples, assume that the carrier makes two revolutions for every 40 inch advance of the web in Example I. From Equation 12:

$$\tan \alpha = \frac{1}{2} \cdot \frac{GD}{BG} = 0.49382$$

$$\alpha = 26^\circ 17'$$

The new spacing, from Equation 13 is:

$$\text{New spacing} = (0.2) \cdot \frac{\cos 26^\circ 17'}{2} = 0.0896''$$

Assuming next that the carrier makes one-half a revolution for each 40 inch advance:

$$\tan \alpha = -1 \cdot \frac{GD}{BG} = -0.98765$$

$$\alpha = -44^\circ 38.6'$$

In the special case where $n = \frac{1}{2}$, it will be seen from Equation 12 that $\alpha = -\theta$.

$$\text{New spacing} = (0.2) \cdot \frac{\cos 44^\circ 38.6'}{\left(\frac{1}{2}\right)} = 0.28460''$$

Upon consideration of the several foregoing examples, it will be apparent that the following general relationship exists:

$$\tan \alpha = \frac{n-1}{n} \cdot \frac{n(CD)}{BG} = \frac{(n-1)(CD)}{BG} \quad (14)$$

in which equation n is equal to the number of turns of the second medium which occur during each linear advance of the first medium, in the direction of movement of that medium; equal to the transverse width of the second medium, and the other quantities are as defined in the foregoing.

It will also be apparent that the thread spacing S , in instances where the second medium comprises a series of longitudinally-extending threads, may be determined by the following formula:

$$S = \frac{\tan \theta (BG \cos \alpha) - BG \sin \alpha}{N} \quad (15)$$

in which equation N is equal to the number of threads comprising the second medium, and the other quantities are as defined previously.

As previously indicated, satisfactory operation of equipment of the general type described in the foregoing requires that the support belt, or the medium which is trained about the mandrel in instances where a belt is

not used, shall move freely about the mandrel. This is especially important in the high speed operation of equipment using a support belt for the medium which is carried on the mandrel, as for example, during the manufacture of crossed thread products of the general type illustrated in Figure 9.

The only effective means so far devised for assuring free movement of such a belt involves the provision of a cushion of air which floats the belt a short distance above the mandrel surface, and a mandrel designed to operate in this manner is illustrated in Figures 12 and 13. It will be understood that the air-flotation type mandrel is suitable for use in apparatus of the type illustrated in Figures 2 and 8, as well as other embodiments in accordance with the invention. It will also be understood that it may be advantageous, in certain instances, to use an air cushion or air flotation mechanism in conjunction with one or more of the supporting guides for the belt structure in those mechanisms which utilize a belt.

The mandrel 119 illustrated in Figures 12 and 13 includes a suitable tubular shell 121 of cylindrical form, which is closed at either end by an annular plate member 123, welded or otherwise affixed to the shell 121. If the mandrel 119 is intended for use in place of the mandrel 14, it may include shaft sections 125 which extend axially therefrom; these may be provided by a single, continuous shaft, or two stub shafts may be used. The outer surface of the tubular shell 121 is provided with a helical groove 127, similar to the mandrel 14, within which there is located a spline or key member 129, which serves as a guide means for defining the path of movement of the belt over the mandrel surface.

In structures embodying a supporting belt, the spline member 129 should project from the surface of the shell a distance approximately equal to the thickness of the belt. The surfaces of the belt and the spline are desirably polished, and may be plated with chromium or other metal, to provide a very smooth, anti-friction surface.

The walls of the shell 121 are provided with a series of spaced, counter-sunk openings 131, which communicate with the interior of the shell. In a particular structure which has proven especially satisfactory in use, the mandrel shell had a length of approximately 120 inches, and a diameter of 12.375 inches, this mandrel being adapted to support a belt having a width of 27 inches which was trained about the mandrel to provide 2 completely supported turns of the belt. The holes had a diameter of $\frac{1}{16}$ inch, and were spaced approximately $3\frac{1}{4}$ inches apart, uniformly on the mandrel surface, so as to underlie the belt in position thereon.

In the mandrel having the dimensions stated above, there were 358 holes in the region of the mandrel engaged by the belt. The counter-sinking provided a maximum diameter at the outlet end of the holes of $\frac{1}{8}$ inch, and the counter-sinking was at an angle of 118° . During operation, pressure air was admitted to the interior of the mandrel so as to maintain the pressure inside the mandrel within the range of from about 3-5 lbs. per square inch, gauge. A single air inlet, such as illustrated at 133 in Figure 12, is satisfactory for this purpose. Under the stated conditions, air will escape through the counter-sunk air discharge openings 131 in sufficient amount to float the belt on the surface of the mandrel. This will reduce the friction between the belt and the mandrel to a very low value, and, as previously noted, is a most important feature in effecting satisfactory operation of the apparatus.

The air discharge openings 131 should be omitted in the region of the mandrel, which is not contacted by the belt or the web medium. Also, when using the air flotation mandrel in conjunction with a supporting belt of porous material, it is of some importance that one surface of the belt, usually the outer surface, shall include a relatively non-porous layer. This may, for ex-

ample, be a layer of polyethylene, tetrafluoroethylene, or other suitable material, adhesively attached to the belt surface. This non-porous layer, especially when it constitutes the outer layer and is made of a material such as polyethylene, or tetrafluoroethylene, performs a dual function. First, it facilitates the removal of the thread or other medium which is applied to the belt during operation of the apparatus, and in addition, it aids, in conjunction with the porous under layer, in accomplishing even flotation of the belt on the mandrel. One example of such a belt is illustrated at 135 in Figure 14, in which view the porous layer of the belt is shown at 137 and the non-porous layer at 139. It will be understood that this belt can be substituted for the belts 17 and 83 of the previously described structures.

In the foregoing, I have disclosed the features of a new, improved method and apparatus for manufacturing a wide variety of cross laid and reinforced products involving the use of mediums which may comprise sheet material of the woven, non-woven or felted type, in combination with other materials of this type or with threads. The invention also makes possible the manufacture of gauze-like materials, having characteristics equal or superior to woven textile materials, at higher speeds, at lesser cost, and with a number of important advantages as compared with woven products. Any types of thread made from natural or artificial fibers or filaments, or combinations thereof, may be used.

I have also set forth in the foregoing various of the important mathematical relationships which exist and which should be followed in the most efficient practice of the invention. In addition, I have disclosed certain mechanical arrangements and structural combinations of especial advantage in carrying out the invention.

Various features of the invention believed to be new are set forth in the accompanying claims.

I claim:

1. An apparatus for forming a continuous web product, comprising a mandrel, a flexible endless belt having at least one complete helical turn on said mandrel, means for depositing a first, elongated flexible medium on said belt, said first medium being carried by said belt about said mandrel, a rotatable carrier having an axis substantially coinciding with the axis of said mandrel, supply means for a second, elongated flexible medium mounted on said carrier, means for guiding said second flexible medium from said supply means over said first flexible medium while said first flexible medium is passing over said mandrel, the second flexible medium being applied in the form of a helix which is wrapped around said first medium in such relationship that the long dimension of said second medium is maintained at a uniform, substantial angle to the long dimension of said first medium in the region where the mediums intersect, and means for cutting said second medium transversely of its long dimension after said second medium has been applied to said first medium.

2. An apparatus for forming a continuous web product, comprising a mandrel, a narrow, elongated guide strip attached to said mandrel and defining a helical path around said mandrel, a flexible endless belt having at least one complete helical turn on said mandrel, a portion of said belt being within said helically disposed guide strip and guided thereby, means for depositing a first, elongated flexible medium on said belt, said first medium being carried by said belt about said mandrel, a rotatable carrier having an axis substantially coinciding with the axis of said mandrel, supply means for a second, elongated flexible medium mounted on said carrier, means for guiding said second flexible medium from said supply means over said first flexible medium while said first flexible medium is passing over said mandrel, the second flexible medium being applied in the form of a helix which is wrapped around said first medium in such relationship that the long dimension of said second medium is main-

tained at a uniform substantial angle to the long dimension of said first medium in the region where the mediums intersect, means for cutting said second medium transversely of its long dimension after said second medium has been applied to said first medium, and means including a source of pressure air and a plurality of air discharge openings provided in said mandrel for providing a cushion of air intermediate said belt and said mandrel during operation of said apparatus, said belt being of multi-layer construction and including at least one layer of non-porous material.

3. An apparatus for forming a reinforced web which comprises a mandrel, guide means on said mandrel, a flexible endless belt trained in a helical form on said mandrel and guided thereon by said guide means, means for moving said belt along said mandrel, means for depositing a sheet along said belt with the machine direction of said sheet lying substantially lengthwise of said belt, said sheet being carried by said belt about said mandrel, a carrier having its axis substantially coinciding with the axis of said mandrel, means for feeding a plurality of strands from said carrier about said sheet while said sheet is in a helical form with the length of said strands being angularly disposed with respect to the machine direction of said sheet, guide means arranged to lay said strands in straight lines across said sheet, means causing relative movement between said carrier and said mandrel, and cutting means for cutting said strands lengthwise of said sheet after said strands are laid over said sheet.

4. An apparatus for forming a reinforced web product having plies thereof with the direction of maximum strength of one sheet being in angular relationship to the direction of maximum strength of another of the constituent sheets comprising a mandrel, a flexible endless belt having at least one complete helical turn on said mandrel, means for moving said belt about said mandrel, means for depositing a first sheet on said belt, said sheet being carried by said belt about said mandrel, a rotatable carrier having an axis substantially coinciding with the axis of said mandrel, a roll of sheet material carried by said carrier, means for guiding the sheet from said roll over said first sheet while said first sheet is passing over said mandrel to provide a line of tangency between said sheets which is generally parallel to the axis of said mandrel, and means for cutting said second sheet after said second sheet has been deposited on said first sheet.

5. An apparatus for forming a reinforced web product comprising a mandrel, a flexible endless belt having at least one complete helical turn on said mandrel, means for moving said belt about said mandrel, means for depositing a first sheet along said belt with the line of maximum strength of said sheet lying substantially lengthwise of said belt, said first sheet being carried by said belt about said mandrel, rotary means associated with said mandrel, a roll of sheet material carried by said rotary means, said roll being oriented to apply a second sheet onto said first sheet in a manner such that the direction of maximum strength of the second sheet is substantially at right angles to the direction of maximum strength of said first sheet, means for rotating said roll about an axis substantially coinciding with the axis of said mandrel, and cutting means operable to cut said second sheet continuously after said second sheet has been deposited on said first sheet.

6. An apparatus for forming a laminated web product comprising a stationary mandrel, a flexible endless belt having at least one complete helical turn on said mandrel, means for moving said belt about said mandrel, means for depositing a first sheet along said belt with the machine direction of said sheet lying substantially lengthwise of said belt, said first sheet being carried by said belt about said mandrel, a carrier disposed about said mandrel and having an axis of rotation substantially coinciding with the axis of said mandrel, a roll of sheet

material carried by said carrier in spaced relation to said mandrel, said roll being angularly disposed with respect to said mandrel to apply on said first sheet, a web of sheet material whose machine direction is substantially at right angles to the machine direction of said first sheet with the second sheet intersecting said first sheet along a line which is generally parallel to the axis of said mandrel, and cutting means operable to cut said second sheet continuously after said second sheet has been deposited on said first sheet.
